UNITED STATES PATENT OFFICE.

WILLIAM R. ARNOLD, OF GENEVA, NEBRASKA.

LAMP-WICK.

1,073,015.

Specification of Letters Patent.

Patented Sept. 9, 1913.

Application filed August 11, 1911. Serial No. 643,611.

To all whom it may concern:

Be it known that I, WILLIAM R. ARNOLD, a citizen of the United States, and a resident of Geneva, in the county of Fillmore 5 and State of Nebraska, have invented certain new and useful Improvements in Lamp-Wicks, of which the following is a specification, reference being had to the accompanying drawings.

10 This invention has relation to certain new and useful improvements in flat textile wicks employed in connection with illuminating lamps and oil stoves, consuming kerosene or similar hydrocarbon oils; and 15 the object of my invention is to provide a wick of this general character of a simple and inexpensive nature and of durable construction so arranged that the wicks will not be consumed and will give an exceedingly 20 large and brilliant flame, absolutely free of smoke and objectionable odors in that the wick is provided with an indestructible reinforcement placed upon opposite sides, insuring complete combustion of the oil without 25 in any way charring or carbonizing the wick.

With these and other objects in view the present invention consists in the combination and arrangement of parts as will be 30 hereinafter more fully described and finally pointed out in the appended claim, it being further understood that changes in the specific structure shown and described may 35 be made within the scope of the claim, without departing from the spirit of the invention.

In the accompanying drawings forming a part of this specification, and in which like numerals of reference indicate similar parts 40 in the several views: Figure 1, shows an elevational view of a wick constructed according to my invention. Fig. 2, is a section on line 2, 2, of Fig. 1. Fig. 3, shows a detail of one of the securing wires, and Fig. 4, 45 shows a vertical section of the upper end of the wick.

As ordinarily made the flat wicks of kerosene oil burning lamps are objectionable in that the burning end of the wick becomes 50 charred and carbonized causing incomplete combustion and resulting in the flame smoking and giving off objectionable odors. In my present invention I provide the ends of the wick with a flat imperforate hood made 55 of a refractory capillary material, as sheet

asbestos, which tips the ends but leaves the edges of the wick exposed.

In the drawings the numeral 1, indicates a flat textile wick the ends of which are tipped with a non-burning reinforcement 60 hood 2, made of sheet asbestos or so called asbestos board. The reinforcement is in the form of two similar square members 2, 2 of a width equal to the width of the wick insuring the top and the edges 3, of the wick being exposed, as shown. Each reinforcement as disclosed covers one side of the burning end of the wick. In order to hold these reinforcements in proper position, I employ one or more wire members 5, preferably 65 made of copper, which are forced through the wick adjacent to the ends of the reinforcements, as shown in Fig. 1, and are then under pressure, forced into the reinforcements as shown in Fig. 2, so that the wires 70 will not project beyond the sides or faces of the wick, insuring the wick working freely within the wick tube of the burner. The ends of these preferably copper wire members 5, are then clenched to securely 75 hold the reinforcements to the end of the wick. In securing the reinforcements the wick end is compressed, so that the thickness of the wick at the reinforced end is no greater than the thickness of the body of 80 the wick as will be understood in referring to Fig. 2. This is necessary in order to insure the free movement of the reinforced wick end within the wick tube of the burner. A wick provided with one of 85 these incombustible hoods, can be readily introduced into the wick tube, and can be easily raised and lowered. In touching a flame to the wick, the generated gases will at once ignite insuring a large, brilliant, 90 smokeless flame. Owing to the impurities within the oil, the reinforcements 2, which never becomes charred or burnt, will, however, finally become clogged with impurities, 95 so that the gas generation will not be so free and perfect as where the capillary qualities of the asbestos reinforcement are perfect. When this occurs, the operator simply reverses the wick and uses the opposite end. An admirable feature of these wicks resides 100 in the fact that they can be turned down very low, as when used in a night lamp or in sick rooms, without giving off any objectionable odors. My wicks are further especially adapted to be used in connection 110

with lanterns, burning with a bright, smokeless flame. It is of course understood that all sizes of flat wicks can be provided with these hoods, which are inexpensive, durable and efficient and can be easily attached to a wick.

Having thus described my said invention, what I claim as new and desire to secure by United States Letters Patent is:

10. The combination with a flat textile wick, of two flat end reinforcements made of sheet asbestos the wick end being compressed so that the thickness of the wick at the reinforced end is no greater than the body of

the wick, said reinforcement leaving the 15 top and edges of the wick exposed, and a plurality of wire members forced through the wick adjacent to the ends of said reinforcements and forced under pressure into said asbestos reinforcements the ends of the 20 wires being clenched, as and for the purpose set forth.

In testimony whereof I affix my signature, in presence of two witnesses.

WILLIAM R. ARNOLD.
